CLAIM

The ornamental design for a RV generator exhaust system, as shown and described.

DESCRIPTION

FIG. 1 shows a front elevational view of an RV generator exhaust system of my design, the left hose being flexible and placeable in any variety of positions;

FIG. 2 illustrates a left side elevational view of the exhaust system as shown in FIG. 1;

FIG. 3 depicts a right side elevational view of the exhaust system as shown in FIG. 1;

FIG. 4 illustrates a rear elevational view of the exhaust system as shown in FIG. 1;

FIG. 5 demonstrates a top plan view of the exhaust system as shown in FIG. 1 along lines 5—5; and,

FIG. 6 pictures a bottom plan view of the exhaust system as shown in FIG. 1 along lines 6—6.
